UNITED STATES PATENT OFFICE

ELIJAH B. SHOTWELL, OF STILLWATER, OKLAHOMA

DIGGING MACHINE

Application filed January 9, 1929. Serial No. 331,186.

This invention relates to digging machines of the type designed for digging post holes, holes for planting trees, as well as holes for shafts, wells and other deep or shallow excavations.

An object of the present invention is the provision of a machine of the above character which is simple and compact in construction and may be readily moved to a desired 10 location, and which may be either manually or power driven, novel means being provided for adapting the machine to power operation.

With the above and other objects in view, the invention further includes the following 15 novel features and details of construction, to be hereinafter more fully described, illustrated in the accompanying drawings and pointed out in the appended claim.

In the drawings:—

20 Figure 1 is a front view of a digging machine constructed in accordance with the invention.

Figure 2 is a side view of the same.

Figure 3 is an enlarged sectional view taken 25 on the line 3—3 of Figure 1.

Figure 4 is a top plan view of the machine.

Figure 5 is a section on the line 5—5 of 30 Figure 1.

Referring to the drawings in detail where- 35 in like characters of reference denote corresponding parts, the machine shown comprises a main supporting frame which includes a base formed of horizontally disposed sills 10. Rising from the base are spaced vertically disposed standards 11, while inclined braces 12 which connect the base and standards serve to stabilize the latter. The upper ends of the standards are connected by means of a beam 13 while inclined braces 14 which 40 connect the beam and standards serve to increase the rigidity of the frame. While the construction described forms a supporting frame which is well adapted for the purpose, of course the particular frame structure may 45 be varied to meet various conditions.

Movable within the supporting frame is a carrier frame which includes spaced parallel beams 15. Mounted upon the beams 15 of the carrier frame are bearing brackets 16 which rotatably support a horizontally dis-

posed shaft 17. Extending downward between the beams 15 of the carrier frame is a vertically disposed hollow cylinder 18, to the upper end of which is secured a beveled gear 19. The gear 19 is spaced above the 55 carrier frame and is supported by anti-friction rollers 20 which are mounted upon said frame and which engage the under face of the gear 19. This gear is thus rotatably mounted upon the carrier frame and in turn 60 rotatably supports the cylinder 18.

Also mounted upon the carrier frame at the outer ends of arms 21 are rollers 22. These rollers engage the outer periphery of the cylinder 18 so as to hold the cylinder in 65 proper position with respect to the carrier and supporting frames.

Removably secured to the lower end of the cylinder 18 as shown at 23 are cutting blades 24. These blades are designed to dig into 70 and cut away the earth when the cylinder is rotated and are removably secured to the cylinder so that blades of different sizes and types may be substituted.

In order to rotate the cylinder 18, the shaft 75 17 carries beveled pinions 25 and 26, one of which is fast upon the shaft, while the other is loose and serves as a steady pinion to hold the gear in proper horizontal position and the cylinder 18 in proper vertical position 80 during the operation of the machine.

The machine is designed to move vertically during its operation as it enters and digs its way into the ground and may be operated either by hand or power. In the former 85 event, a crank arm 27 may be mounted upon the outer end of the shaft 17 and this shaft operates through slots 28 provided in the standards so as to permit of vertical movement during the operation of the machine.

The machine may also be operated by power and for this purpose there is provided a rotatably mounted shaft 29 having one of its ends mounted in a member 30 carried by the 90 supporting frame while its other end may be mounted in a suitable bearing and driven by any suitable means. The shaft 29 has mounted thereon a sprocket 31, while the shaft 17 has mounted thereon a sprocket 32. A chain 100

33 trained around these sprockets serves to rotate the shaft 17.

In order to compensate for the vertical travel of the shaft 17, this shaft and the shaft 29 are connected by lazy tongs 34 which carry idler sprockets 35 around which the chain 33 is trained. By reference to Figures 1 and 2 of the drawings it will be seen that as the shaft 17 descends, the sprockets 35 will be separated so as to compensate for the position of this shaft. As the shaft 17 moves upward, the sprockets 35 will move relatively inward as will be readily understood.

In order to remove the earth from the hole 15 the invention includes an elevator which comprises spaced chains 36 which carry buckets or shovels 37. The chains 36 pass around a lower sprocket 38 and upper sprockets 39, 40 and 41 in the order named so that the earth is carried upward and dumped into a discharge chute 42 at the upper end of the cylinder 18.

The elevator is driven from the shaft 17 by means of a sprocket and chain drive 43 and gears 44. The elevator and its driving means 20 are movable vertically with the movement of the cylinder 18 and of course do not rotate with this cylinder.

In order to raise and lower the cylinder 18, a bail 43 is provided for connection with one 30 end of a cable 44 and this cable is trained over pulleys 45 and has its outer end adapted for detachable connection with the shaft 17.

The blades may be lowered to engage the ground by unwinding the cable from the 35 shaft 17 and the cable thereafter removed from the shaft during the operation of the machine. When it is desired to remove the blades from the hole, the cable 44 is rewound upon the shaft 17 so that the machine may be elevated.

40 A partition 47 is provided within the cylinder 18 between the chains 36.

The invention is susceptible of various changes in its form, proportions and minor 45 details of construction and the right is herein reserved to make such changes as properly fall within the scope of the appended claim.

Having described the invention what is claimed is:—

50 In a digging machine, a supporting frame including spaced vertically disposed standards and a horizontal beam connecting the upper ends of the standards, a carrier frame including spaced horizontally disposed beams 55 movably positioned between the standards, a vertically disposed cylinder supported by and rotatable within the carrier frame, an elevator operating within the cylinder, a beveled gear rigid with the cylinder, a shaft rotat- 60 ably supported upon the carrier frame and extending through the standards, means operatively connecting said shaft and cylinder to rotate the latter when the shaft is rotated, a cable guided over the horizontal beam of the 65 supporting frame and having one end se-

cured to the elevator and its other end detachably wound upon the shaft to regulate the height of the elevator, means to rotate the gear, cutting blades at the lower end of the cylinder, and means to operate the elevator.

70 In testimony whereof I affix my signature.

ELIJAH B. SHOTWELL.
